UNITED STATES PATENT OFFICE

MARVIN W. MOESTA, OF DETROIT, MICHIGAN, ASSIGNOR TO MURRAY BODY CORPORATION, OF DETROIT, MICHIGAN, A CORPORATION OF MICHIGAN

DOOR LATCH

Application filed July 7, 1925. Serial No. 41,988.

This invention relates generally to latches, particularly designed for vehicle doors, and consists of certain novel features of construction, combinations and arrangements of parts as will be more fully described and particularly pointed out in the appended claims.

In the accompanying drawing:

Figure 1 is a horizontal sectional view through a door with my latch applied there-

10 to.

Figure 2 is a fragmentary side elevation of the latch embodying my invention.

Figure 3 is a perspective view of the latching bolt.

15 Referring now to the drawing, the numeral 1 designates a door, preferably of a vehicle body, having a pillar 2 that is connected at its inner and outer edges to suitable sheet metal panels 3 and 4 respectively and that 20 supports a channel-shaped strip 5 which constitutes a runway for a vertically movable glass window panel 6. As shown, the pillar 2 is preferably constructed of sheet metal and is substantially Z-shape in cross section, 25 while the strip 5 is also constructed of sheet metal and holds a suitable channel-shaped felt guide 7 for the window panel. In order that maximum vision may be obtained, the base of the strip 5 is preferably secured directly to the inner face of the pillar 2. Hence 30 a wider glass panel 6 may be used.

Mounted upon the inner panel 4, preferably within a depressed portion 8 thereof, is a suitable latch having a wedge-shaped 35 latching bolt 10 which is adapted to engage a suitable keeper (not shown) to hold the door in closed position. As shown, the bolt 10 is preferably hollow and is arranged so that the rearwardly diverging arms 11 and 40 12 respectively thereof extend through suitable slots 13 and 14 respectively in the pillar 2 at opposite sides of the channel-shaped runway 5. The inner arm 12 of the bolt is preferably pivoted at its rear end to spaced 45 lugs 15 struck out from the transversely ex- 50 tends flange 16 of the case plate 17, while the outer arm 11 is adapted to swing between the runway 5 and outer panel 3. Thus, the bolt 10 straddles the runway 5 and will not interfere with the vertical movement of the

glass panel 6. Any suitable means such as the spring 18 may be used for normally retaining the bolt in projected position. As shown, this spring 18 has a portion coiled about the pivot 19 for the bolt and has forwardly and rearwardly projecting arms 20 and 21 respectively that bear against the inner arm 12 of the bolt and inner face of the case plate 17.

For retracting the bolt 10 from the inner side of the door, I preferably provide a vertical spindle 22 having a crank portion 23 for actuating a short link 24 pivotally connected to the bolt 10. As shown, the spindle 22 is journaled vertically with aligned brackets 25 secured to the case plate 17 and may be actuated by any suitable handle (not shown), while the link 24 has an elongated slot 26 receiving the crank portion 23 of the spindle and has a vertical opening 27 for receiving the pivot pin 28 which is parallel to the pivot 19 for the bolt. This pivot 28 is preferably carried by spaced lugs 29 projecting laterally from the upper and lower edges of the inner arm 12 of the bolt. In order that the crank portion 23 of the spindle will normally be in operative position with respect to the rear end of the slot 26 in the link 24, a portion 30 of the case plate is preferably pressed inwardly to form a stop for the crank portion 23 of the spindle, while a spring 31 is preferably used to hold the crank portion 23 aforesaid against the stop 30. As shown, this spring 31 has an intermediate coil portion 35 surrounding the spindle 22 and is terminally secured to the spindle and case plate.

For retracting the bolt 10 from the outer side of the door, I preferably provide a crank 32 having the inner arm 33 thereof extending through an elongated slot 34 in the outer arm 11 of the bolt and having the outer arm 35 thereof rigidly secured to the shank 36 of a suitable handle 37. This handle 37 may be any suitable construction but preferably has an escutcheon plate 38 secured by screws 39 to the outer panel 3 of the door. Any suitable means such as the spring 40 may be employed for normally holding the handle 37 in horizontal position so that the inner arm 33 of the crank 32 will normally 45 50 55 60 65 70 75 80 85 90 95 100

be held in operative position against the rear end of the slot 34 in the outer arm 11 of the bolt. As shown, this spring 40 has a coiled intermediate portion sleeved upon 5 one of the screws 39 and is provided with projecting arms 41 and 42 respectively which bear against the crank 32 and pillar 2.

Thus, from the foregoing description, it 10 will be readily apparent that the operation of the bolt 10 will not interfere with the vertical movement of the glass panel 6 at any time. It will also be apparent that the inside and outside bolt retracting means may be independently operated. Moreover the 15 arrangement is such that a small case plate may be used, hence a substantially compact construction is provided. Furthermore the spindle 22 directly engages the link 24, hence the usual sliding shank is dispensed with entirely and the desired results are secured with 20 the use of fewer parts.

While it is believed that from the foregoing description the nature and advantages of the invention will be readily apparent, I desire to have it understood that I do 25 not limit myself to what is herein shown and described, and that such changes may be resorted to when desired as fall within the scope of what is claimed.

30 What I claim as my invention is:

1. In a latch, the combination with a case plate, of a latching bolt having diverging arms, a pin connecting one of said arms to the case plate, said arm having a projection, a 35 pin carried by the projection, and actuating means for the bolt including a spindle having a crank portion, and an operating connection between the spindle and bolt including a link having a slot receiving the crank portion of the spindle and having an opening 40 receiving the second mentioned pin.

2. In a latch, the combination with a case plate, of a latching bolt having diverging arms, means for actuating the bolt including 45 an operating handle having a crank portion at one end engageable with one of said arms, a spindle journaled on the case plate and having a crank portion, and an operating connection between the spindle and bolt including a link having a portion receiving the crank portion of the spindle.

3. In a latch, the combination with a bolt having diverging arms, and a projection upon one of said arms, of actuating means for said 55 bolt including a vertically disposed spindle having a crank portion, and an operating connection between said bolt and spindle including a pin carried by the projection aforesaid, and a link having a circular opening receiving the pin and having an elongated slot 60 receiving the crank portion of said spindle.

4. In a latch, the combination with a latch bolt, having a pivoted arm and a projection upon said arm, a vertically arranged spindle adjacent to said bolt having a crank portion,

a pin carried by said projection, and a link having openings receiving said pin and the crank portion aforesaid of said spindle.

5. In a latch, the combination with a pivoted latch bolt, of a pin carried thereby, and actuating means for said bolt including an upright spindle having a crank portion, and a link having a circular opening receiving said pin and having an elongated slot receiving the crank portion of said spindle. 75

6. In a latch, an upright spindle having a crank portion, an operating shank extending at substantially right angles to said spindle and having a crank portion at one end thereof, a latch bolt pivotally mounted adjacent 80 said spindle and having a longitudinally extending slot in a portion thereof receiving one of the crank portions aforesaid, and a link pivotally connected to said bolt and having a longitudinally extending slot therein receiving 85 the other of the crank portions aforesaid.

7. In a latch, a horizontally mounted latch bolt having an upright pivot and having an elongated slot at a point remote from said pivot, and actuating means for said bolt including a rotatable shank having a crank portion disposed at substantially right angles to 90 said pivot and extending through the elongated slot in said bolt.

8. In a latch, an upright spindle having a 95 crank portion; a link having a slotted connection with said crank portion, a pin carried by said link, a rotatable shank and crank portion, and a pivotally mounted latch bolt having a circular opening receiving said pin and 100 having an elongated slot receiving the crank portion of said shank.

In testimony whereof I affix my signature.

MARVIN W. MOESTA.
